UNITED STATES PATENT OFFICE.

FRANTZ KAWEKY, OF NEW YORK, N. Y.

WINDOW-CHAIR.

SPECIFICATION forming part of Letters Patent No. 589,177, dated August 31, 1897.

Application filed May 12, 1897. Serial No. 636,181. (No model.)

To all whom it may concern:

Be it known that I, FRANTZ KAWEKY, a citizen of the United States, and a resident of New York, in the county of New York and State of New York, have invented certain new and useful Improvements in Window-Chairs, of which the following is a specification.

This invention relates to a window-chair of novel construction and designed to provide a safe and comfortable support for a person cleaning the window.

In the accompanying drawings, Figure 1 is a perspective view of my improved window-chair; Fig. 2, a vertical cross-section on line 2 2, Fig. 1; Fig. 3, an inverted plan; Fig. 4, a detail of the rack-and-pinion mechanism; and Fig. 5, a section on line 5 5, Fig. 4.

The letter *a* represents the seat of my improved window-chair, to which are secured the depending side pieces *b*, terminating at their outer ends in short squared legs *b'*, which are adapted to rest upon the window-sill.

Below the inner end of the seat *a* there are secured thereto by means of straps *c* the laterally-movable racks *d*, engaged at the center by a common pinion *e*. The outer end of each rack *d* is doubled or provided with a transverse arm *d'*, and both the racks and the arms have upturned ends *d''*, surrounded by flexible buffers *f*. When the racks are by the revolution of the pinion moved laterally outward, these buffers will tightly bind against the sides of the window-frame, so as to securely lock the chair in place without, however, scratching or otherwise injuring the window.

The arbor *e'* of the pinion *e* passes through the central strap *c* and through a counter-sunk bearing-plate *g* of a reinforcing-strip *a'*, which is secured below the inner edge of seat *a*. The upper end of the arbor *e'* is squared and is adapted to be engaged by a suitable key *A*, which may be passed through a key-hole-guard *h*, secured to the upper side of

seat *a*. This guard is provided with two diametrically-placed T-shaped slots *h'*, through which may be passed a correspondingly-shaped bolt *i*, that is adapted to engage the teeth of the rack and pinion, Fig. 4, and thus lock the racks in place. The object of providing two slots *h'* is to permit the bolt to be brought into engagement with either one of the racks, and thus its engagement is assured, even though one of the slots is obstructed by one of the rack-teeth.

The operation of the window-chair will be readily understood. It is placed in position upon the sill, the racks are moved outward by means of the key, so as to bear tightly against the sides of the window-frame, and then the bolt is inserted to lock the racks in their distended position. To remove the window-chair, the bolt is withdrawn, when the racks will be released and may be pushed inward to become disengaged from the window. A folding back and arm rest *j*, pivoted to the side pieces *b*, prevents the occupant of the chair from falling.

What I claim is—

1. In a window-chair, the combination of a seat with a pair of laterally-movable racks having upturned ends, buffers secured to such ends, a pinion engaging the racks, and a bolt for locking the racks, substantially as specified.

2. In a window-chair, the combination of a seat with a pair of laterally-movable racks, straps embracing the same, a pinion engaging the racks, a key-plate having a pair of bolt-holes, and a bolt adapted to engage either one of said holes and to lock the racks, substantially as specified.

Signed at New York, in the county of New York and State of New York, this 10th day of May, A. D. 1897.

FRANTZ KAWEKY.
